United States Patent Office

Des. 192,894
Patented May 22, 1962

192,894

ROOF VENTILATOR

Gillette V. Patterson and Fred P. Darnell, Cleveland,
Ohio, assignors, by mesne assignments, to Swartwout
Fabricators, Inc., Kokomo, Ind., a corporation of
Indiana

Filed Sept. 10, 1959, Ser. No. 57,498

Term of patent 14 years

(Cl. D62—4)

Fig. 1

FIGURE 1 is a perspective view of a roof ventilator, embodying our new design;

FIGURE 2 is a side elevational view thereof; and

FIGURE 3 is a top plan view thereof.

We claim:

The ornamental design for a roof ventilator, substantially as shown.
